(57) **CLAIM**

The ornamental design for a bottle, as shown and described.

DESCRIPTION

FIG. 1 is a front elevational view of a bottle according to my new design, the rear elevational view being a mirror image; FIG. 2 is a top plan view thereof;

FIG. 3 is a left side elevational view thereof, the right side elevational view being a mirror image; and,

FIG. 4 is a bottom plan view thereof.

The dash-dash-dash broken lines shown in the drawings are included for the purpose of illustrating environmental structure and form no part of the claimed design.

The dot-dash-dot-dash broken lines shown in the drawings define the top and bottom boundaries of the claimed design.
